UNITED STATES PATENT OFFICE

JOHN E. DOMAGALL, OF PERU, ILLINOIS, ASSIGNOR TO W. H. MAZE COMPANY, OF PERU, ILLINOIS, A CORPORATION OF ILLINOIS

DEVICE FOR SETTING GLAZIERS' POINTS

Application filed July 25, 1928. Serial No. 295,339.

This invention relates to a device for setting glaziers' points.

The main objects of this invention are to provide and improve devices for facilitating the setting or driving in place of glaziers' points; to provide a device of this nature which will save time and labor in work of this character; and to provide a device which may be easily and readily struck by a driving tool without liability of striking and bruising the finger of the workman.

An illustrative embodiment of this invention is shown in the accompanying drawings in which:

Fig. 1 is a view in perspective of my improved device.

Fig. 2 is a sectional view taken on the line 2—2 of Fig. 3.

Fig. 3 is a fragmentary plan view of my improved device in use on a window pane showing the manner in which it abuts the glazier's point.

Heretofore in the setting of glaziers' points, it has been the usual procedure to place the point on the pane of glass and hold it in position with the end of the finger. Due to the smallness of even the largest size of glazier's point as compared to the size of the usual workman's finger, it has been somewhat difficult to strike the point with a hammer or such tool without striking the finger holding the point. Furthermore, glaziers' points are made of thin metal and if the tool used to strike the point does not have a square

sharp corner at the edge of its striking face, the striking tool will slip over the glazier's point instead of engaging it. By using my improved device, the workman's finger holds both the glazier's point and the setting tool, the square face of which abuts against one edge of the point. The setting tool extends

well out from the finger holding it and an upstanding shoulder on the outer end thereof, provides a very good abutment which may

be struck by any convenient tool such as a common carpenter's hammer.

In the construction shown in the drawings my improved device comprises an elongated strip or blade 1 of thin sheet steel which has a bearing face 2 at one end thereof, disposed at right angles to the plane of the strip, for engaging or abutting against one edge of a glazier's point 3. The strip 1 is preferably tapered inwardly toward the other or outer end, and said end is bent at 4 and inclined upwardly then reversely bent at 5 to provide an upstanding shoulder 6 which is adapted to be struck by a suitable driving tool such as a hammer.

The portion forming the shoulder 6 is preferably bent downwardly at right angles to the plane of the strip 1, so that the outer face thereof is parallel to the face 2 at the opposite end of the device.

In the use of this device, the glazier's point 3 is placed against the pane of glass 7 and held in position by the workman's finger, the improved setting device is then placed on the pane and slipped into position with the face 2 thereof abutting against the outer edge of the glazier's point. A portion of the workman's finger which holds the glazier's point also bears on the strip 1 so as to hold it in proper position.

The upstanding shoulder 6 is then struck by a suitable driving tool such as a hammer and the glazier's point set in the window sash 8 to the required depth.

Although but one specific embodiment of this invention has been herein shown and described, it will be understood that details of the construction shown may be altered or omitted without departing from the spirit of this invention as defined by the following claim.

I claim:

A device of the class described comprising an elongated unitary strip of sheet steel, the face of the edge at one end of said strip being

at right angles to the plane of said strip, said face being adapted to abut against a glazier's point when placed in the same plane therewith, the other end of said strip being inclined upwardly and then downwardly at right angles to the plane of said strip to form a shoulder adapted to be struck by a driving tool.

In testimony whereof I have hereunto set
10 my hand at Peru, Illinois, this 21st day of
July, 1928.

JOHN E. DOMAGALL.
